UNITED STATES PATENT OFFICE

2,109,622

SYSTEM OF TRANSMITTING IMAGES

John W. McKay, Brooklyn, N. Y., assignor to
National Television Corporation, Wilmington,
Del., a corporation of Delaware

Original application February 6, 1933, Serial No.
655,350, now Patent No. 2,056,974, dated Octo-
ber 13, 1936. Divided and this application
September 12, 1935, Serial No. 40,271

7 Claims. (Cl. 178—7.6)

This invention relates to a system of transmitting images from one place to another by scanning an object field, transmitting the plurality of light and dark elements thus obtained into a continuous series of impulses, and translating said impulses into light again and arranging them in an orderly manner to form the image.

In transmitting images by television at the present time, an object field is cut up into a plurality of lines, these lines being scanned successively at the transmitting end and re-arranged again by a scanning device at the receiving end. There is no particular standard for the number of lines per picture for transmitting images. In some cases as low as forty-five lines per picture have been used with good results while in other cases, especially where more detail is desired, 120 lines may be desirable or even as high as 180 lines per picture.

20 It is one of the objects of the present invention to provide a television system which is usable for transmitting images at different numbers of lines per picture.

Another object of the invention is to provide a television apparatus which may be changed to transmit or receive a different number of lines per picture while the machine is in operation.

Another object of the invention is to provide a television system in which the number of lines per picture may be changed without changing the size of the picture.

Other objects and objects relating particularly to the construction and assemblage of the various parts will be apparent as the description proceeds.

The invention is illustrated in the accompanying drawings in which:

Fig. 1 is a fragmentary front elevational view of a scanning disc incorporating the invention;

40 Fig. 2 is a fragmentary elevation of the same disc showing a different position of the parts thereof;

Fig. 3 is a sectional side elevational view of the scanning disc arrangement showing the controlling means thereof;

Fig. 4 is a front sectional view of the disc taken on the line 4—4 of Fig. 3; and

Fig. 5 is a top sectional view of the sleeve for moving the relative position of the discs taken on the line 5—5 of Fig. 3.

This application is a division of my co-pending application Serial No. 655,350, filed February 6, 1933 now Patent 2,056,974, granted Oct. 13, 1936.

55 In the arrangement shown I provide a scanning disc 254 rigidly attached to a flange 255, by

means of screws 256, the flange forming a part of a sleeve 257 keyed to a motor shaft 258 which is rotated by the motor 259. A glow lamp 260 is positioned behind the disc 254 and a lens 261 is positioned in front of it so as to enlarge the image built up by the disc as the size of such image is necessarily limited by the circumference of the disc. The lens 261 is mounted in the front of a cabinet 262. The disc 254 comprises an opaque disc of metal or other opaque material and is provided with a plurality of holes 263 (Figs. 1 and 2) arranged in a spiral around the circumference of the disc in a manner well known in the art, so that the outermost hole is spaced from the innermost hole a distance corresponding to the height of the picture to be received, while the distance between every two holes is equal to the width of the picture.

Such a disc rotating at the proper speed in front of the light 260 will completely scan an area on the illuminated electrode of the lamp equal to the size of the picture to be received, and as the light is modulating in accordance with the incoming television signal the picture appears on the edge of the disc. For a sixty line picture there are necessarily sixty of the holes 263. If it is desired, however, to make the apparatus changeable over to a one hundred and twenty line picture, I provide a plurality of holes 264 positioned midway between the holes 263 but having a diameter half the size of the diameter of the holes 263. If the holes 264 were the same size as the holes 263 and the one hundred twenty holes were permitted to scan the object field or the light source, the lines of light formed would overlap due to the fact that the diameter of the holes 263 are just sufficient to permit each hole to trace one line across the picture without overlapping. While the holes are shown somewhat exaggerated in the figure, it is well known in the art that this must be the relation between the diameters thereof and the spacing of the holes.

In front of the disc 254 and adapted to rotate with it I position a second disc 265 having a serrated spiral edge. The serrated edge of the disc 265 is formed of a plurality of fingers 266 positioned in such a way that they will normally extend outwardly between the holes 263 so as not to interfere in any way with these holes but to cover the holes 264 as is clearly illustrated in Fig. 1. Each of the fingers 266 is, however, provided with a small hole 267 which is normally covered by the disc 254 and hence serves no purpose when the disc 265 is positioned as it is in Fig. 1 for the sixty line picture. However, when

it is desired to shift to the one hundred and twenty line picture, the disc 265 is rotated slightly counterclockwise with respect to the disc 254 with the result that the fingers 266 each cover one of the holes 263 thereby exposing the holes 264 as is clearly indicated in Fig. 2. That portion of each of the fingers 266 which contains the hole 267 will then fall directly over one of the holes 263, thereby cutting down the size of the hole 263 to that of the holes 264, the holes 267 in the fingers 266 being exactly the same size as the holes 264.

It will thus be seen that when the discs are in the position shown in Fig. 1, sixty holes will be arranged in the disc for scanning, but when the second disc 265 is moved to the position indicated in Fig. 2, there will be one hundred and twenty holes equally spaced and of the same diameter. It will, however, be evident that the height of the picture which is determined by the radial distance between the outermost and innermost hole will remain the same for both the sixty line and one hundred and twenty line picture, while the width of the one hundred and twenty line picture will be half that of the sixty line picture. This alteration in the proportion of the received image is compensated for by a cylindrical lens (to be later described), which is automatically moved between the disc and the observer and tends to widen the picture to its proper dimension.

In Fig. 3 is shown the mechanism for moving the disc 265 with respect to the disc 264. To this end a sleeve 268 is rotatably mounted upon the sleeve 251 and is provided with a flange 269 to which the disc 265 is attached. The sleeve 268 may be held against axial movement on the sleeve 251 by means of a washer 270 which in turn is held by a nut 271 threaded on the reduced end 272 of the sleeve. The sleeve 268 is provided with a pair of grooves 273 which are curved so that one end is offset from the other as shown in Fig. 5. The sleeve 251 is also provided with a pair of grooves 274 which are parallel to the axis of the sleeve and align with one end of the grooves 273 when the discs are in their sixty line picture position and with the other end of the grooves 273 when the discs are in their one hundred and twenty line picture position. A pair of pins 275 extend through the grooves on each side of the shaft and are mounted in a ring 276 which rotates in a ball race 277, mounted in a sleeve 278 against a flange 279 on one side and secured by a ring 280 on the other, threaded into the end of the sleeve.

The ring 276 with its pins is free to rotate with the scanning element, but upon axial movement thereof, the pins slide in the grooves 273 and 274 and cause the slight rotation of the disc 265 with respect to the disc 254 necessary to change from a sixty line picture to a one hundred and twenty line picture.

Axial movement of the ring 276 and associated parts is accomplished by moving the sleeve 278 axially. This is done by mounting the sleeve 278 for axial movement in a tubular member 281 to which it is keyed by the key 282 to prevent rotation therein. The sleeve is provided with an end closure 283 in which is a tapped hole 284 adapted to receive the threaded end of a shaft 285, the other end of which is mounted for rotation in a bearing 286 in the end 287 of the tubular member 281. This end is secured against the front wall of the cabinet and the shaft extends

through an opening 288 and is provided with a knob 289 on the outside for manual manipulation. A pair of collars 290 and 291 are provided attached to the shaft on the outside and inside of the end wall 287 of the tubular member 281 so as to prevent axial movement of the shaft 285. 5

Rotation of the knob will cause the shaft to be directed into or out of the end plate 283 of the sleeve 278 and thereby cause the sleeve to move backward and forward depending on which way the knob is rotated. This will move the ring 276 and associated pins axially which will cause the relative movement between the discs 254 and 265 as already described. The shifting of the discs may thus be accomplished independently of the 15 rotation thereof.

In order to compensate for the difference in width of the picture for a one hundred and twenty line picture as compared to a sixty line picture, I provide a cylindrical lens 292 which is mounted 20 in a movable arm 293 attached to a sleeve 294. The sleeve 294 fits around the tubular member 281 and is held against a rib 295 formed on the tubular member by a ring nut 296 which is screwed onto the threaded end of the member. Thus 25 mounted the arm 293 can oscillate about the tubular member, throwing the lens 292 into and out of position in front of the viewing lens 261. To oscillate the arm 293 I provide a small pinion 297 on the shaft 285 which meshes with an idler gear 298 rotatably mounted on a lug 299 attached to the inside of the tubular member 281 by means of a pin 300. The gear 298 has its upper edge 30 extending through an opening 301 provided for that purpose in the upper edge of the tubular 35 member 281, and meshes with rack teeth 302 provided on the inner end of the sleeve 294. The operator, therefore, has only to turn the knob 289 in order to shift both the lens and the discs to change from a sixty line picture to a one hundred and twenty line picture, and this change may be made regardless of the speed of the apparatus.

While the lens 292 has been shown as a cylindrical lens adapted to alter the image vertically and thus cut down its height, it is evident that a 45 concave cylindrical lens might be used to increase the width of the image so as to make it the same size for either picture.

From all the above description, it is evident that I have provided a scanning apparatus for 50 television in which the number of lines per picture may be altered and such alteration may be made while the machine is in motion so that it is possible to change from one system to another providing the apparatus is designed for those particular systems. While in the arrangement shown two systems only are usable, it is evident that the apparatus may be designed to accommodate more than two systems by suitable changes in construction of the apparatus. 55

Where the number of pictures per second sent out by the transmitting station is the same for systems of different numbers of lines per picture the speed of the motor will be the same. However, it is obvious that if one system has a different number of pictures per second the speed of the scanning element will have to be altered. This may be done by using a motor having different synchronous speeds or by arranging suitable change speed gearing so that the speed of the 65 scanning element may be set for the desired number of pictures per second.

The apparatus has been described in connection with receiving television apparatus but it is obvious to those skilled in the art that the same 75

devices are adaptable to transmitting television apparatus by the substitution of a light-sensitive cell for the modulated light used or the substitution of a bright constant source of light for the modulated light while a bank of light-sensitive cells is positioned around the subject whose picture is being transmitted. It is, therefore, thought unnecessary to show a transmitting apparatus as the parts are essentially the same, and the invention is intended to cover both transmitting and receiving devices.

Many modifications may be made in the structure shown and described without departing from the spirit of the invention, and I do not, therefore, desire to limit myself to what has been shown and described except as such limitations occur in the appended claims.

What I desire to secure by Letters Patent and claim is:

- 20 1. A television apparatus comprising a scanning disc, a plurality of spaced apart apertures around the circumference of said disc in the form of a spiral, a plurality of smaller diameter apertures equally spaced around said disc on the same spiral line as said first apertures, there being one of said second apertures between every two of said first apertures, and means to alternatively block off said second apertures or uncover said second apertures and reduce the diameter of said first apertures.
- 25 2. A television apparatus comprising a scanning disc, a plurality of equally spaced apertures around the circumference of said disc in a spiral, a plurality of smaller diameter apertures also equally spaced around the circumference of said disc on the same line as said first apertures, there being one of said second apertures between every two of said first apertures, a second disc positioned in juxtaposition to said first disc and having a spirally cut edge coming within the line formed by said apertures on said first disc, a plurality of fingers extending outwardly from the edge of said second disc, said fingers being spaced apart the same distance as said first series of apertures, an opening in each of said fingers equal in size to said apertures, and means to alternatively rotate said second disc through a slight angle with respect to said first disc whereby said fingers either cover said second series of apertures or cover said first series of apertures with the openings in said fingers in a line with said first mentioned apertures.
- 30 3. A television apparatus comprising a scanning disc, a plurality of equally spaced apertures around the circumference of said disc in the form of a spiral, a plurality of smaller diameter openings also equally spaced around said disc on the same line as said first mentioned apertures, there being one of said second apertures between every two of said first mentioned apertures, a second disc in juxtaposition to said first disc and rotatably mounted with respect thereto, said second disc having an edge which conforms to the spiral of said apertures but is less in diameter than said spiral, a plurality of fingers extending outwardly from the edge of said second disc, said fingers being equally spaced apart on the edge thereof with the spacing similar to the spacing of said first mentioned apertures, a hole in each of said fingers equal in size to said second mentioned apertures, means to alternatively move said second disc with respect to said first disc so that said fingers either cover said second apertures with portions of said disc covering the openings in said fingers, or said fingers cover said first
- 35 4. A scanning device comprising a scanning disc, a plurality of apertures in said disc arranged in a spiral to scan with a predetermined number of lines per picture, a second set of scanning apertures in said disc arranged to cooperate with said first set to scan said picture with a different number of lines per picture, means to cover said second set of apertures when the device is used for scanning at said first mentioned number of lines per picture, means cooperating with said last mentioned means to decrease the size of said first mentioned scanning apertures when said second mentioned apertures are uncovered, a member rigidly secured to said first mentioned scanning disc, a second member rigidly secured to said second mentioned disc, a groove in said first member, a groove in said second member, a pin adapted to engage the grooves of both of said members, and means to move said pin while said discs are rotating, said grooves being so arranged that movement of said pin will cause said members to rotate with respect to each other.
- 40 5. In a device of the class described a scanning disc, means on said disc to intercept and control light directed against said disc so as to scan a field with a number of lines, a second scanning disc mounted adjacent said first disc, means on said second disc adapted to cooperate with the means on said first disc to change the effective number of said first-mentioned means so as to change the number of scanned lines when said discs are rotated through a slight angle with respect to each other, a member having a slot therein attached to said first disc, a second member having a slot therein attached to said second disc, a pin adapted to engage both of said slots, and means to move said pin in said slots while said discs are rotated, said slots being so arranged that movement of said pin therein will cause relative movement of said members.
- 45 6. A scanning device comprising a pair of closely positioned scanning discs, one of said discs having means to intercept and control light directed against said disc so as to scan a field with a number of lines, means on the other of said discs adapted to cooperate with said first-mentioned means to alter the effective number of said first-mentioned means and change the number of scanning lines when said discs are rotated through a slight angle with respect to each other, a shaft, means to secure one of said discs to said shaft, a sleeve attached to said means and having a groove therein extending longitudinally of said shaft, a second sleeve mounted rotatably on said first sleeve and secured to said second disc, said second sleeve having a groove therein extending longitudinally of said shaft, the slots in said sleeve being inclined at a slight angle with respect to each other, a pin engaging the slots in both of said sleeves, a ring surrounding said sleeves and rotatably mounted with respect thereto, said pin being rigidly attached to said ring, and means to move said ring and pin longitudinally of said sleeves while said discs are rotating whereby the movement of said pin in said slots changes the relative rotation of said discs.
- 50 7. A scanning apparatus comprising a pair of closely positioned scanning discs, one of said discs having means to intercept and control light di-

apertures with the openings therein in a line with said first apertures, and optical means to compensate for the difference in width between the scanned image scanned by said first apertures alone and by said first and second apertures together.

5

10 4. A scanning device comprising a scanning disc, a plurality of apertures in said disc arranged in a spiral to scan with a predetermined number of lines per picture, a second set of scanning apertures in said disc arranged to cooperate with said first set to scan said picture with a different number of lines per picture, means to cover said second set of apertures when the device is used for scanning at said first mentioned number of lines per picture, means cooperating with said last mentioned means to decrease the size of said first mentioned scanning apertures when said second mentioned apertures are uncovered, a member rigidly secured to said first mentioned scanning disc, a second member rigidly secured to said second mentioned disc, a groove in said first member, a groove in said second member, a pin adapted to engage the grooves of both of said members, and means to move said pin while said discs are rotating, said grooves being so arranged that movement of said pin will cause said members to rotate with respect to each other.

15

15 5. In a device of the class described a scanning disc, means on said disc to intercept and control light directed against said disc so as to scan a field with a number of lines, a second scanning disc mounted adjacent said first disc, means on said second disc adapted to cooperate with the means on said first disc to change the effective number of said first-mentioned means so as to change the number of scanned lines when said discs are rotated through a slight angle with respect to each other, a member having a slot therein attached to said first disc, a second member having a slot therein attached to said second disc, a pin adapted to engage both of said slots, and means to move said pin in said slots while said discs are rotated, said slots being so arranged that movement of said pin therein will cause relative movement of said members.

20

25 6. A scanning device comprising a pair of closely positioned scanning discs, one of said discs having means to intercept and control light directed against said disc so as to scan a field with a number of lines, means on the other of said discs adapted to cooperate with said first-mentioned means to alter the effective number of said first-mentioned means and change the number of scanning lines when said discs are rotated through a slight angle with respect to each other, a shaft, means to secure one of said discs to said shaft, a sleeve attached to said means and having a groove therein extending longitudinally of said shaft, a second sleeve mounted rotatably on said first sleeve and secured to said second disc, said second sleeve having a groove therein extending longitudinally of said shaft, the slots in said sleeve being inclined at a slight angle with respect to each other, a pin engaging the slots in both of said sleeves, a ring surrounding said sleeves and rotatably mounted with respect thereto, said pin being rigidly attached to said ring, and means to move said ring and pin longitudinally of said sleeves while said discs are rotating whereby the movement of said pin in said slots changes the relative rotation of said discs.

30

35 7. A scanning apparatus comprising a pair of closely positioned scanning discs, one of said discs having means to intercept and control light di-

40

45 55 8. A scanning device comprising a scanning disc, a plurality of apertures in said disc arranged in a spiral to scan with a predetermined number of lines per picture, a second set of scanning apertures in said disc arranged to cooperate with said first set to scan said picture with a different number of lines per picture, means to cover said second set of apertures when the device is used for scanning at said first mentioned number of lines per picture, means cooperating with said last mentioned means to decrease the size of said first mentioned scanning apertures when said second mentioned apertures are uncovered, a member rigidly secured to said first mentioned scanning disc, a second member rigidly secured to said second mentioned disc, a groove in said first member, a groove in said second member, a pin adapted to engage the grooves of both of said members, and means to move said pin while said discs are rotating, said grooves being so arranged that movement of said pin will cause said members to rotate with respect to each other.
